HEAD COVERING

Sybil Price, New York, N. Y.

Application January 3, 1950, Serial No. 136,537

4 Claims. (Cl. 132—49)

1

The present invention relates to apparel and is particularly directed to a head covering of the type worn for holding the hair in place.

Accordingly, an object of the present invention is to provide such a head covering which is extremely simple in construction and is economical to manufacture.

Another object is to provide such a head covering which affords proper ventilation for the hair.

Another object is to provide such a head covering which is readily adjustable to more nearly conform to the shape of the head.

Another object is to provide such a head covering which is effectively retained on the head of the wearer.

Another object is to provide such a head covering which is adapted to withstand such rough usage to which it may normally be subjected.

A further object is to provide such a head covering which lends itself to a great variety of uses.

Other and further objects of the present invention will be manifest from the following description and the accompanying drawing.

In accordance with the invention, the foregoing objects are accomplished by providing a head covering which comprises an annular or substantially cap-like body member of net fabric provided with spaced annularly extending resilient elements, such as rubber-like strands, which may be incorporated into the fabric during its formation or subsequent thereto. The body member may be formed of a strip of fabric of greater length than width having lengthwise extending strands, the strip being stitched or otherwise secured at its lengthwise ends to form an annular structure. The annular or cap-like member has an opening in the top or apex which may be constricted, for example, by a draw string or the like, and the lower edge or head opening of the member may be formed with a hem enclosing the strip adjacent that edge. When a hem is employed at the lower edge a wider strip of elastic material may be inserted therein, stitched thereto, or secured in any desired manner. It is to be understood that no hem may be provided, in which event the lower strand or resilient element or elements will serve to constrict the head opening, whereby the covering will comfortably fit the wearer.

A preferred embodiment of my invention is illustrated in the accompanying drawing, wherein:

Fig. 1 is a perspective or side view of a head covering in accordance with the invention;

2

Fig. 2 is a front elevational view of the head covering shown in Fig. 1;

Fig. 3 is a rear view of the covering, showing the stitched edges thereof;

Fig. 4 is a plan view of the strip of material from which the covering is made;

Fig. 5 is a sectional view taken along the line 5—5 of Fig. 6;

Fig. 6 is an enlarged fragmentary elevational view of a portion of the head covering adjacent the lower edge thereof; and

Fig. 7 is a perspective view of the head covering with the top thereof shown closed.

Referring to the drawing in detail, there is shown a head covering comprising a body member 8 constructed from a strip of material having its lengthwise edges secured together by stitching providing a seam 10 to form an annular, generally hemispherical cap or cap-like structure having an opening 12 at the top or apex thereof.

The strip is formed of net or mesh fabric material, as shown in Figs. 4 and 6 which is provided with lengthwise extending spaced apart resilient elements, such as rubber-like strands 14, which, when the strip is formed into a garment extend annularly in substantially parallel spaced relation. The strands 14 may be double, that is, a pair of adjacent strands of resilient material, may be employed as shown in Fig. 5, or a single spaced strand may be employed if desired. Accordingly, when reference is made herein to spaced resilient elements, it is to be understood to refer to single spaced strands or to a pair of strands adjacent each other, the pairs being spaced from each other. Preferably, the strip is cut from a width of fabric formed by a warp knitting machine wherein the strands 14 are warp threads incorporated into the fabric, although it will be appreciated that the fabric may be formed in any other suitable manner, the strands being applied thereafter.

The fabric may have any desired net, mesh or lace pattern which has openings of a size for affording ventilation when the covering is worn.

The rubber-like strands 14 preferably are quite yieldable so that the covering is comfortable and does not derange the coiffure but are adapted to securely retain the covering on the head of the wearer. The strands may be formed of uncovered rubber or rubber-like material or may have a twisted or braided covering of yarn applied thereto which matches or contrasts with the color of the fabric.

The edge 16 of the strip defining the opening, as well as the lower edge 18 thereof preferably is

provided with a hem 20 (Fig. 4) which may enclose and substantially connect the strand 14 adjacent the respective edge. The hem at the lower edge 18 may have a separate strand of elastic material 15 therein as shown in Fig. 5. Such hem gives the edge an attractive appearance and prevents unravelling of the fabric at the edge. If desired a ruffling 17 or other trim may be attached to the covering adjacent one or both openings.

Suitable means, such as a draw string 22, may be provided at the edge 16 for constricting and substantially closing the opening as shown in Fig. 7, the ends of the string being adapted to be tied in a bow or knot. Instead of a draw string, a tape or other means may be employed to constrict the opening. By so constricting the opening the head covering may be adjusted to more nearly conform to the head of the wearer and the size thereof to accommodate the particular coiffure.

The head covering, as shown, is extremely simple in construction and is adapted for a wide variety of purposes. For example, the covering may be worn as a hair net, a hair training device usually worn at night, a device worn while drying the hair, or as a device to assist in arranging the coiffure or to retain the same in a desired arrangement. The head covering is washable and can readily withstand such rough usage to which it normally may be subjected. The strands serve as ribbing which reinforce the net fabric and at the same time cause the fabric to conform to the head. Since the cap can be made by utilizing conventional machines, it can be constructed in an economical manner. The head covering when not in use, can be folded together very compactly to facilitate storage in a very small space, for example, in a handbag or the like, whereby it may be readily carried by the wearer for use whenever desired.

In view of the foregoing description it will be seen that the present invention provides a simple and practical head covering.

While I have illustrated and described one embodiment of my invention, it is to be understood that I do not wish to be limited to the precise structure thereof, as obviously various modifications and changes may be made therein without departing from the spirit and scope of my invention.

What I claim is:

1. A head covering of the class described comprising a cap-like body member of net fabric having a crown portion and a bottom opening, and a plurality of pairs of elastic strands interwoven in the net fabric of the body member with the strands of each pair adjacent each other and the pairs of strands disposed in spaced relation relatively to each other between the crown portion and bottom opening, said strands extending circumferentially of the cap-like body member for conforming the body member to the shape of the head.

2. A head covering of the class described comprising a cap-like body member of net fabric having a crown opening and a bottom opening, a plurality of pairs of elastic strands interwoven in the net fabric of the body member with the strands of each pair adjacent each other and the pairs of strands disposed in spaced relation relatively to each other between the crown opening and bottom opening, said strands extending circumferentially of the cap-like body member for conforming the body member to the shape of the head, and a hem enclosing another elastic member adjacent said bottom opening.

3. A head covering of the class described comprising a cap-like body member of net fabric having a crown opening and a bottom opening, a plurality of pairs of elastic strands interwoven in the net fabric of the body member with the strands of each pair adjacent each other and the pairs of strands disposed in spaced relation relatively to each other between the crown opening and bottom opening, said strands extending circumferentially of the cap-like body member for conforming the body member to the shape of the head, a hem enclosing another elastic member adjacent said bottom opening, and a draw string adjacent the crown opening for constricting said crown opening.

4. A head covering of the class described comprising a cap-like body member of net fabric having a crown opening and a bottom opening, a plurality of pairs of rubber-like strands interwoven in the net fabric of the body member with the strands of each pair adjacent each other and the pairs of strands disposed in spaced relation relatively to each other between the crown opening and bottom opening, said strands extending circumferentially of the cap-like body member for conforming the body member to the shape of the head, a hem enclosing another rubber-like member adjacent said bottom opening, said rubber-like member being of a greater width than the said strands, and a draw string adjacent the crown opening for constricting said crown opening.
